ROBERT WOERNER, OF MANNHEIM, GERMANY.

MACHINE FOR PRESSING CIGARS.

1,399,235.

Specification of Letters Patent.

Patented Dec. 6, 1921.

Application filed September 2, 1916. Serial No. 118,293.

(GRANTED UNDER THE PROVISIONS OF THE ACT OF MARCH 3, 1921, 41 STAT. L., 1313)

To all whom it may concern:

Be it known that I, ROBERT WOERNER, a subject of the German Emperor, residing at Mannheim, in the Grand Duchy of Baden and German Empire, have invented a new and useful Improved Machine for Pressing Cigars, of which the following is a specification.

My present invention relates to a machine 10 for pressing cigars, which differs essentially and favorably from existing machines used for the purpose by the fact that packets of cigars of different widths and heights, consisting of cigars of any desired form, can 15 be pressed equally well, and indeed in large or small quantities.

The new device has, further, the advantage that the horizontal press plates necessary for exercising the vertical pressure, 20 are always moved parallel to each other, and indeed also when the press is not uniformly filled. Consequently the jamming which occasionally occurs in existing presses is effectually avoided. This latter object is 25 obtained by the double support of the press plates required for producing the vertical pressure and of the press tables carrying the press slides and by the adjustability of these parts according to the shape of the cigars to 30 be pressed. In order to be able to effectually press packets of different breadths and heights and cigars of different forms in the new press, and in order to prevent either a too strong or an insufficient pressure being 35 used, it is absolutely necessary to adjust the horizontal and vertical pressure permissible for the different forms of cigars before the pressing process commences. For this purpose indicating devices are provided, ac- 40 cording to my invention, which enable the horizontal and vertical pressure to be previously regulated by a foreman and which, during the work, and afterward, show whether the prescribed pressure has been 45 observed. The use of scales in such presses is indeed not new, but heretofore such scales have been used in another connection than in my invention, and the existing devices agree neither in design nor operation with 50 the new arrangement I claim.

On the accompanying drawing representing my invention by way of example, Fig. 1 is a cross section of the machine, Fig. 2, a side elevation of the same, Fig. 3, an elevation, and Fig. 4 a cross section, of the pressure indicator, Fig. 5, a side elevation, and Fig. 6 a cross section, of the purchase roll used in the indicating device,

Fig. 7 shows a detail on a larger scale. 60 The cigar press has principal pressing plates 1 which act on pressing bars 2 designed to press against the cigars contained in the press slides.

The principal pressing plates 1 are carried by the spindles 3 having counter screw threads 4 and 5.

On the spindles 3 sit further the pressure rods 8 and 9, which ride on counter screw threads 11 and 12 of said spindles. The tie 70 rods 6, 7 carry the supports 14 and 15 of the tables 13 on which the press slides are provided, and these supports have slots 14^a and 15^a.

The tie rods 6, 7 end in a screw spindle 16 75 which is connected by a nut with the wheel 31. Said rods 6, 7 have further a slot to allow the spindle 3 to pass through. For the purpose of avoiding superfluous friction the wheel 31 rests in a ball bearing 54, provided in the bearing 55.

The described parts are put into operation by a crank 18, the rotation of which is transferred either to the spindles 3 or to the spur-wheel 31. 85

For the purpose of driving the spindle 3 there is a miter wheel 20 on the spindle 19 which can be brought into engagement with a miter wheel 21. This wheel 21 sits on a spindle 22, the ends of which carry miter 90 wheels 23 which engage in the miter wheels 24.

In order to operate the parts for producing the vertical pressure a spindle 25 is provided, at the lower end of which is provided the miter wheel 26, and at its upper end the bevel wheel 27. The bevel wheel 27 engages in the bevel wheel 28 on the spindle 29, at the opposite end of which sits a bevel wheel 30 which engages in the bevel wheel 31. 95 32 100

is a U-shaped cross bar, while 33 and 34 are parts of the frame which end in the feet 35 and 36.

The two devices for obtaining the vertical pressure are connected together by spindles 37 provided with suitable bevel wheels, and the devices for producing the horizontal pressure by the bevel wheels provided on the spindle 38.

10 The indicator devices for adjusting the vertical pressure consist of two indicators 39, 40, of which the latter can be adjusted into any desired position by the key 41. The indicator 39 sits on the axis of a roll 15 42 which is connected with the double roll shown in Fig. 5 by a steel wire or the like, said wire 43 being fastened to the larger part 44 of the roll, while from the smaller part 45 a wire 46 passes to the movable vertical press bars. As a consequence every moment of the vertical press bars is transferred to the indicator 39.

In a quite similar manner the device for measuring the horizontal pressure is arranged. In this case the indicator 47 (Fig. 2) is connected with the spindle 3, whose movement is transferred to said indicator. The other indicator 52 is adapted to be moved by a key.

30 The described device is operated as follows:

The cigars, in press slides of known construction, are placed on the tables 13 and then the bevel-wheel 20 is brought into engagement with the bevel-wheel 21. By then turning the crank 18 the parts by which the horizontal pressure is exerted are moved toward each other. At the same time are moved the principal plates 1, the independent pressing bars 2, and the pressure rods 40 8, 9.

With the pressure rods 8, 9 the vertical pressing bars 48 connected thereto are all moved. These rods have slots 48^a so that their movement toward each other is not hindered by the tie rods 6, 7.

The press bars 2 for exerting the horizontal pressure, before beginning the press process, are adjusted according to the 50 packet to be treated, and, by so doing, the bars 48 fastened to the rods 8 and 9 and required to exert the vertical pressure, are automatically adjusted.

As shown in Fig. 2, 49' is an end view 55 of a frame, while 49 in Fig. 1 indicates the manner of pressing cigars in layers of twelve or thirteen cigars in a row in the frame 49'. In the drawing the pressure rods 8, 9 have their widest position.

60 50 indicates the manner of pressing the cigars in the so called block form, in which each layer only has 10 cigars and the pressing plates for the horizontal pressure are correspondingly closer together. The 65 pressing plates or bars 48 for exerting the

vertical pressure are shown so near together that their lower members touch each other.

For the purpose of producing the vertical pressure the bevel wheels 51 and 26 are 70 brought into engagement with each other, after the bevel wheels 20, 21 have been separated. By turning the crank 18 the tie rods 6, 7, and the tables 13, are raised, and, by so doing, the cigars are pressed against the 75 pressing bars 48, by which the vertical pressure is effected.

In order to regulate the maximum horizontal and vertical pressure, before the pressing process is commenced, the indicator 40 is 80 adjusted for the horizontal pressure, and the indicator 52 is adjusted for the vertical pressure. This is effected by the foreman with a key over the scales. Thereafter the crank 18 is turned until the indicators 39 and 47 85 arrive in the same angular position as the indicators 40 and 52 respectively.

With the object of enabling the operator to ascertain whether the desired pressure has been exceeded the indicators 39 and 47 are 90 provided with tappets or stops, so that they force the indicators 40 and 52 out of their position when the pressure is too high. The foreman, who notes the positions given to the indicators 39 and 47, is therefore able to 95 determine whether his regulations have been observed. The stops on the indicators 39 and 47 must of course only be on one side, so that when these indicators move back again after exceeding the maximum pressure 100 the indicators 40 and 52 remain in the highest position to which they have been moved.

The indicators are covered by a glass plate so that they cannot be tampered with by 105 the workmen.

What I claim and desire to secure by Letters Patent of the United States is:—

1. In a machine for pressing cigar packets of different sizes, the combination with the press table adapted to carry the press slides containing the cigars, of means to support said table on both sides, means to move said supporting means and thus said table vertically, pressing bars against which the packets of cigars are pressed when said press table is vertically moved, and means to adjust the position of said pressing bars according to the size of the packets of cigars before exerting the horizontal pressure, substantially as set forth. 110 115 120

2. In a machine for pressing cigar packets of different sizes, the combination with the press table adapted to carry the press slides containing the cigars, of means to support said table vertically, pressing bars against which the packets of cigars are pressed when said press table is vertically moved, and horizontally movable pressure rods carrying said pressing bars, substantially as, and for the purpose, set forth. 125 130

3. A machine for pressing cigar packets of different sizes, comprising in combination, a press table, tie rods adapted to carry said press table, a screw spindle carrying 5 said tie rods, and a spur-wheel with screw threaded bore on said screw spindle, substantially as, and for the purpose, set forth.

In testimony whereof I have signed my name to this specification in the presence of two subscribing witnesses.

ROBERT WOERNER.
